DETACHABLE PULL TAB FOR SLIDE FASTENER SLIDERS

Alfred E. Carlile, Meadville, Pa., assignor to Talon, Inc., a corporation of Pennsylvania

Application March 16, 1940, Serial No. 324,335

14 Claims. (Cl. 24—205.5)

This invention relates to slide fasteners and, in particular, to the sliders thereof.

It is an object of this invention to provide a reversible slider construction, for slide fasteners, which slider may be operated from either side of the fastener.

It is a further object of this invention to provide such a slider construction wherein opposite sides of the slider are provided with similar pull tab supporting lugs.

It is a further object of this invention to provide detachable slide fastener pull tab constructions, particularly adapted for use on sliders of the above-described type.

These and other objects and advantages of the invention will appear from the following description taken in conjunction with the accompanying drawing which forms a part thereof, and will be pointed out in the appended claims.

In the drawing:

Fig. 1 is a view, in perspective, of a slide fastener slider according to this invention, as applied to a slide fastener;

Fig. 2 is a side view, partly in section and partly in elevation, of the slider of Fig. 1, illustrating the manner in which the detachable pull tab member is attached thereto;

Fig. 3 is a view similar to Fig. 2, but with the pull tab partly in section;

Fig. 4 is a perspective view of a modified form of slider;

Fig. 5 is a front view of the slider shown in Fig. 4, with the pull tab detached;

Fig. 6 is a view similar to Fig. 4, of a slider according to Fig. 4, with a second modified form of detachable pull tab; and

Fig. 7 is a perspective view of the pull tab shown in Fig. 6 in its closed position.

In some uses of the slide fastener and, in particular, in their use on reversible garments such as jackets, it is desirable that the slider may be operated from opposite sides.

Heretofore, sliders have been manufactured with lugs of different type at opposite sides of the slider, and with separate pull tabs attached to each lug. In such constructions, one of the pull tabs was of the pin lock type and the other of the non-locking type.

In other constructions, the pull tab was mounted upon a track or retaining slide which extended from one wing or side of the slider, over the neck or wedge of the slider, and onto the other wing or side of the slider.

In the first of the above-described constructions, the existence of a swingable pull tab, at all

times, upon the underside of the slider was extremely disadvantageous inasmuch as it was subject to catching in clothing or the skin of a wearer of the garment to which the slide fastener was attached and rendered the slider unit extremely bulky, unwieldy and inconvenient.

In the second of the above-described constructions, the production of the track or slide which supported the pull tab was extremely costly and, in addition, the track or slide was of such size and configuration as to catch in the clothing or skin of the wearer in the same manner as did the extra pull tab on the underside of the slider in the first-described construction, and as to impart to the slider unit the above-described disadvantages.

These disadvantages are totally obviated according to this invention, by forming a slider with opposite sides or wings of similar form and provided with similar pull tab supporting lugs, to one of which lugs, a pull tab constructed according to this invention is detachably secured. When it is desired to operate the slider from the opposite side, it is merely necessary to detach the pull tab from the lug at one side of the slider and secure it, detachably, to the lug at the opposite side of the slider.

Referring to the drawing in detail, the slide fastener shown in Fig. 1 comprises a pair of stringers 10 and 11, each formed of textile or other stringer tape 12 having one edge thereof suitably reinforced at 14 and having complementary interlocking fastener members 15 secured in suitable manner to the reinforced edge of the stringer tape 12. The lower ends of the stringer tapes 10 and 11 are secured together by suitable known means such as the bottom stop 14a. While a regular or non-separating bottom stop is shown, it is, of course, to be understood that the principles of this invention are applicable to fasteners having other types of bottom stops, or separating end fittings.

The slider is generally designated 16 and comprises a pair of similar sides or wings 17 connected at their upper ends by a wedge or neck 18 and provided with marginal side flanges 19 which terminate in spaced relationship to one another for accommodating extension of the stringer tapes 12 therebetween in order that the slider 16 may slide freely upon the interlocking fastener members 15 and be engaged and disengaged thereby to open and close the fastener in known manner.

Each wing 17 is provided with an upstruck lug 20 of loop form, beneath which a locking aper-

ture, or locking pin receiving aperture 21 may, optionally, be provided. The wings 17 being similar, the apertures 21 will be similarly disposed with respect to each wing 17 or, in other words, as seen in Fig. 1, the aperture 21 will appear to the right of the upper wing 17 and the lower aperture 21 will appear to the left of the lower wing 17 (not shown). The lugs 20 do not project substantially from the planes of the wings 17 and, therefore, do not catch upon the under garments or skin of a wearer.

Particularly adapted for use with the above-described slider body construction is the pull tab shown in Figs. 1 to 3, which is generally designated 22. This pull tab is of plate-like form having the upper or inner end bent over to form a hook portion 23. Fixed at one end to the underside of the outer, plate-like portion of the pull tab 22, is a yieldable spring-like member 24, preferably of leaf form. This member, due to its inherent resiliency, has the upper or inner, free end thereof constantly biased outwardly into engagement with the end of the hook portion 23 to form therewith a closed loop. The hook portion 23 and leaf spring member 24 thus form clamping members engageable with either of lugs 20. One of these members is yieldable or resilient and the other is non-yieldable. They are maintained in clamping position by the inherent resiliency in the resilient member 24.

Optionally, where the slide body 16 is provided with apertures 21, as above described, an upper or inner end extremity of the pull tab member 22, adjacent the hook portion 23 is bent downwardly, preferably at substantially 90 degrees from the plane of the pull tab member proper, to form the locking pin 25 which, in operation, will project through an aperture 21, as shown in Fig. 3, lockingly to engage interlocking fastener members 18 in the fastener member receiving channel of the slider body 16, in the flat or lowermost position of the pull tab member 22.

When the pull tab 22 is attached to the lug 20 at one side of the slider 16 and where it is desired to operate the slider from the opposite side, it is merely necessary to bring the pull tab to the position shown in Fig. 1, press the free end of the spring member 24 toward the adjacent plate-like portion of the pull tab member 22 and then withdraw the hook portion 23 and locking pin 25 from below the lug 20 to detach the pull tab from the slider body.

In order to attach the pull tab 22 to the opposite side of the slider, the pull tab is placed in the position of Fig. 2 and thrust toward the slider body and then pulled downwardly of the slider body to the position of Fig. 3, whereupon the spring member 24 will automatically move outwardly to engage the hook portion 23, as shown in Fig. 3, detachably to secure the pull tab 22 swingably to the slider body.

In the embodiment illustrated in Figs. 4 and 5, the slider body 16a is similar to the above-described slider body 16, save that the lugs 20a thereof are of modified form, being in the form of upstanding bosses provided with transverse pivot recesses or bores 20b for rotatably, or pivotally, receiving suitable pivot projections on a pull tab. As in the construction illustrated in Figs. 1 to 3, the locking apertures 21 may be provided, optionally, in substantially the same location in the wings 17, as in the construction of Figs. 1 to 3.

The pull tab, illustrated in Figs. 4 and 5, is generally designated 32. This pull tab 32 is of

bifurcated form having a plate-like outer end portion 33, from which extends a pair of legs 34 having inwardly directed, facing, pivot projections 35 at their extremities. Due to the inherent resiliency of the material of the pull tab member 32, the legs 34 are normally biased outwardly of one another beyond parallelism.

The outward movement of the legs 34 is limited by a slidable clamping band or clamping member 36 in the form of a continuous, closed, band. This band 36 is adapted to rest in a pair of grooves 37 in the outer edges of the legs 34 to release the legs 34 sufficiently to allow them to spread to such degree, as shown in Fig. 5, that the ends of the projections 35 will be spaced at a distance greater than the width of the lugs 20a. A similar pair of grooves 38 is disposed inwardly of the grooves 37 and, when the band is slidably thrust inwardly of the pull tab 32 toward the inner end thereof into engagement with the grooves 38, the inner ends of the legs 34 are brought together and the projections 35 thereof are thrust into the recesses or bores 20b and maintained therein.

When it is desired to remove the pull tab 32 from one side of the slider 16a and to attach it to the opposite side of the slider, it is merely necessary to thrust the clamping band 36 outwardly of the pull tab from the grooves 38, as shown in Fig. 4, to the grooves 37, whereupon the legs will be spread, as shown in Fig. 5. The projections 35 are then aligned with the recesses or bores 20b and the clamping band thrust inwardly of the pull tab member 32 to engagement with the grooves 38 whereupon the projections 35 will be clamped in the recesses or bores 20b, as shown in Fig. 4.

Where locking apertures 21 are provided, optionally, as described above, one leg 34 is provided with a projection or locking pin 50 at the end thereof adjacent its projection 35, which locking pin 50 will project through either of the locking apertures 21, as shown in Fig. 4, lockingly to engage interlocking fastener members 18 in the channel of the slider 16a.

In the embodiment illustrated in Figs. 6 and 7, the slider body 16a and its lugs 20a are similar to the above-described slider body 16a and lugs 20a of the embodiment illustrated in Figs. 4 and 5. The pull tab member, designated 42, is, however, of different constructions. The pull tab member 42, as illustrated, comprises a pair of blade-like or plate-like members 43 pivotally connected at 44 by means of a rivet, or other pintle means, in such manner that they may move in the same manner as the blades of a pair of shears. Inwardly of the plate-like portions of the members 43 is a pair of offset leg portions 45 which are coplanar and which terminate in inwardly directed, facing, projections 46 similar to the above-described projections 35 and cooperating with the recesses or bores 20b of the lugs 20a in similar manner.

Spaced from the apertures through which the pintle means 44 extends, the upper member 43 is provided with a downstruck portion 47 which is adapted, upon alignment of the members 43 in closed position, as shown in Fig. 7, to engage a complementary downstruck portion 47 in the lower member 43. This engagement of the downstruck portions 47 prevents accidental displacement of the members 43 from the closed position when they are placed in that position, as shown in Fig. 7. Any suitable aperture means 48 may be provided in the plate-like portions of

the members 43 for alignment in the closed position to accommodate suitable tension means, such as ribbons, thongs, or the like.

Where locking apertures 21 are provided in the wings 17 of the slider body 16a, as described above, one of the leg portions 45 of the members 43 is provided with a locking pin member 49 which extends through one of the apertures 21, as shown in Fig. 6, in the locked position of the slider, lockingly to engage interlocking fastener members 15 in the channel of the slider body 16a.

When it is desired to remove the pull tab member 42 from one side of the slider body 16a and attach it to the other side thereof, the members 43, which are locked in the position of Fig. 7, are moved pivotally apart to the position shown in Fig. 6, whereby to separate the projections 46 thereof sufficiently to permit removal of these projections 46 from the receiving recesses or bores 20b. The pull tab member 42 is then removed from that side of the slider. It may be attached to the opposite side of the slider by reverse movement of the members 43 from the position of Fig. 6 to the position of Fig. 7 after one of the projections 46 has been aligned with the recesses or bores 20b.

It is, of course, to be understood that the above description is merely illustrative of the principles of this invention and in nowise limiting and that I desire to comprehend within this invention all modifications included within the scope of the appended claims.

Having thus fully described my invention, what I claim as new and desire to secure by Letters Patent is:

1. In combination, a slide fastener slider having similar sides, each side provided with a similar pull member supporting lug, and a pull member embodying means for detachably connecting said pull member with either of said pull member supporting lugs.

2. In combination, a slide fastener slider having similar sides, each provided with a similar pull tab supporting lug, and a pull tab member embodying means for detachably connecting said pull tab member with either of said pull tab supporting lugs, said last-named means including at least one yieldable member and an associated non-yieldable retaining member.

3. In combination, a slide fastener slider having similar sides each provided with a similar pull tab supporting lug, and a pull tab member embodying means for detachably connecting said pull tab member with either of said pull tab supporting lugs, said last-named means including a pair of leg members on said pull tab member with pivot projections at their ends, said pivot projections being engageable with complementary receiving means in said pull tab supporting lugs, and means for retaining said leg members in closed position.

4. In combination, a slide fastener slider having similar sides each provided with similar pull tab supporting lugs, and a pull tab member embodying means for detachably connecting said pull tab member with either of said pull tab supporting lugs, said last-named means including a pair of members clampingly engageable with either of said lugs.

5. The combination defined in claim 4, and means associated with said last-named members for retaining said members in clamped position.

6. In combination, a slide fastener slider having similar sides each provided with a similar

pull tab supporting lug, and a pull tab member embodying means for detachably connecting said pull tab member with either of said pull tab supporting lugs, said last-named means comprising a hook portion at the inner end of said pull tab member engageable with said lugs, and a leaf spring member secured at one end to the underside of said pull tab member and having the free end thereof engageable with said hook portion and constantly biased toward engagement therewith.

7. A detachable pull tab member for use with slide fastener sliders having lugs of loop form, said pull tab member comprising a plate member having a hook portion at its inner end and a leaf spring member attached at one end to the underside of said plate member at its outer end and having its free end engaging the interior of said hook portion and forming with said hook portion a closed loop adapted to surround an attached lug.

8. A detachable pull tab member for use with slide fastener sliders having lugs of loop form and adjacent locking pin apertures, a plate member with a hook portion at its inner end and a leaf spring member having one end attached to the underside of said plate member and having its free end engaged and biased toward the interior of said hook portion, and a locking pin on said plate member adjacent said hook portion adapted for projection through said locking pin aperture for engaging slide fastener members in the slider.

9. A detachable pull tab member for use with slide fastener sliders having lugs in the form of bosses with transverse pivot recesses, said pull tab member comprising a bifurcated member having a plate-like portion at its outer end with laterally spaced legs extending longitudinally therefrom, said legs having facing oppositely directed transverse pivot projections at their extremities, said legs being normally spread apart beyond parallelism by their inherent resiliency, and a clamping band slidably longitudinally of said legs for holding them in closed position and maintaining the pivot projections in said pivot recesses, or releasing them.

10. A detachable pull tab member for use with slide fastener sliders having lugs in the form of bosses with transverse pivot recesses, said pull tab member comprising a bifurcated member having a plate-like portion at its outer end with laterally spaced legs extending longitudinally therefrom, said legs having facing oppositely directed transverse pivot projections at their extremities, said legs being normally spread apart beyond parallelism by their inherent resiliency, and a clamping band slidably longitudinally of said legs for holding them in closed position and maintaining the pivot projections in said pivot recesses, or releasing them, said legs having recesses complementary with said clamping band and defining the open and closed positions of said legs.

11. A detachable pull tab member for use with slide fastener sliders having lugs in the form of bosses with transverse pivot recesses and adjacent locking pin apertures, said pull tab member comprising a bifurcated member having a plate-like portion at its outer end with laterally spaced legs extending longitudinally therefrom, said legs having facing pivot projections at their extremities, said legs being normally spread apart by their inherent resiliency, a clamping band slidably longitudinally of said legs for hold-

ing them in closed position and maintaining the pivot projections in said pivot recesses, or releasing them, and a locking pin on one leg projectable through said locking pin apertures for locking said slider.

12. A detachable pull tab member for use with slide fastener sliders having lugs in the form of bosses with transverse pivot recesses, said pull tab member comprising a pair of plate members pivotally connected intermediate their ends and having leg members extending longitudinally therefrom, facing pivot projections at the ends of said leg members engageable with the pivot recesses in said lugs in the closed position of said legs and complementary detent means on said plate members for retaining said legs in closed position by retaining said plate members in fixed relationship.

13. A detachable pull tab member for use with slide fastener sliders having at each side lugs in the form of bosses with transverse pivot recesses and adjacent locking pin apertures, a pair of plate members pivotally connected intermediately

10 their ends and with leg members extending longitudinally therefrom, facing pivot projections at the ends of said leg members engageable with said pivot recesses in the closed position of said legs, and complementary detent means on said plate members for retaining said legs in closed position by maintaining said plate members in fixed relationship, and a locking pin on one of said legs projectable through said locking pin apertures for locking said slider.

14. In combination, a slide fastener slider having similar sides each provided with a similar pull tab supporting lug, and each side having a locking pin receiving aperture adjacent said lug, and a pull tab member embodying means for detachably connecting said pull tab member with either of said pull tab supporting lugs, and said pull tab member having thereon a locking pin projectable through either of said locking pin receiving apertures to lock said slider upon attachment of said pull tab member to the lug adjacent said aperture.

ALFRED E. CARLILE.
